US00D974406S

(12) **United States Design Patent** (10) **Patent No.:** **US D974,406 S**
(45) **Date of Patent:** **** Jan. 3, 2023**

(54) **DISPLAY SCREEN WITH ICON**

(71) Applicant: **Google LLC**, Mountain View, CA (US)

(72) Inventor: **Sehee Lee**, Brooklyn, NY (US)

(73) Assignee: **GOOGLE LLC**, Mountain View, CA (US)

(**) Term: **15 Years**

(21) Appl. No.: **29/807,718**

(22) Filed: **Sep. 14, 2021**

Related U.S. Application Data

(63) Continuation of application No. 29/807,519, filed on Sep. 13, 2021, now Pat. No. Des. 959,488, which is a continuation of application No. 29/807,335, filed on Sep. 10, 2021, which is a continuation of application No. 29/722,872, filed on Feb. 3, 2020, now Pat. No. Des. 933,710, which is a continuation of application No. 29/695,509, filed on Jun. 19, 2019, now abandoned, which is a continuation of application No. 29/643,554, filed on Apr. 10, 2018, now abandoned.
